UNITED STATES PATENT OFFICE.

FRITZ DICKENSCHIED, OF BERLIN, GERMANY, ASSIGNOR TO GENERAL ELECTRIC COMPANY, A CORPORATION OF NEW YORK.

INCANDESCENT LAMP.

1,149,188.

Specification of Letters Patent. Patented Aug. 10, 1915.

Application filed July 26, 1912. Serial No. 711,612.

To all whom it may concern:

Be it known that I, FRITZ DICKENSCHIED, a subject of the Emperor of Germany, residing at Berlin, Germany, have invented 5 certain new and useful Improvements in Incandescent Lamps, of which the following is a specification.

The present invention relates to incandescent lamps, and comprises an improvement 10 in the mounting of metallic filaments therein.

My invention is directed to the prevention of deleterious effects at regions of contact 15 of the filament and its supports. In accordance with my invention the temperature of this region of the filament is lowered by increasing its radiating surface, as by flattening the filament.

In the accompanying drawings, Figure 1 20 illustrates the mounting of an incandescent lamp in accordance with my invention, and Figs. 2 and 3 are enlarged detailed views of a filament having one region flattened to increase its radiation.

25 The necessity of equipping incandescent lamps provided with elongated, slender metallic filaments, such as illustrated in the drawing, with supports for the filament is accompanied with certain disadvantages 30 which are especially evident when employing supports consisting of metals having a lower melting point than the filament. Because of the high operating temperature of the filament, the supports are highly heated 35 at the region of contact. This results in some cases in gases being given off which after a time result in a lowered vacuum in the lamps and a consequent deterioration of the filament by electric discharges. In some

40 cases it may even happen that the holder wire is melted at its point of contact with the filament, thereby releasing the filament. Even when it is attempted to prevent the overheating of the supporting wire by increasing its diameter, alloys are apt to be formed at its contact with the filament resulting in the filaments burning through at this point. As it is desirable to make the supports somewhat springy to prevent 45 displacement on the part of the filament, the

size of the supporting wires is limited as the larger wires are not sufficiently resilient.

As above indicated, the excessive heating of the holders by contact with the filament is prevented in accordance with the present 55 invention by increasing the surface of the filament at the contact region and thereby increasing the radiation. As the energy is thus dissipated more readily, the temperature is necessarily lowered. In the case of 60 round filaments my invention may be readily carried out by locally flattening the filament as by pressing or rolling. This local flattening may be produced by simply pressing the filament 2 by hand with pinch- 65 ers at the region 2, where it comes into contact with holder wires 3. In some cases the local flattening of the filament may advantageously take place after the filament has been wound upon the supports, and in other 70 cases the filament is pressed flat at regions at measured distances corresponding with the regions of contact with the holders.

Of course, it will be understood that my 75 invention is not limited to a filament mount containing a plurality of loops as illustrated in Fig. 1 but is equally applicable to a mounting in which a simple looped filament is provided with a single support intermediate to its ends to hold it in position. 80

What I claim as new and desire to secure by Letters Patent of the United States, is,—

1. In an incandescent lamp, the combination of a support, an elongated, slender metallic filament held thereby, the radiating surface of said filament being greater 85 at the region of contact with the support than elsewhere, whereby the radiation is increased at this region.

2. In an incandescent lamp, the combination of a holder, a metallic filament supported thereby at an intermediate point, said filament being locally flattened at the region of contact with the holder. 90

In witness whereof, I have hereunto set 95 my hand this 12th day of July, 1912.

FRITZ DICKENSCHIED.
